Henry R. Finch, knight of Canastoga Co.
Letters Patent dated Aug 3d 1851
(No 400)

The Schedule referred to in these Letters Patent, and making part of the same
to all whom it may concern

Be it known that I Henry R. Finch, knight of Canastoga Township, County
of Lancaster and State of Pennsylvania have invented a new Design of cast
iron Tomb which I style the "Cemetery Tomb" and do hereby declare
that the following is a full and exact description thereof, reference being
had to the accompanying drawings and to the letters of specification made
thereon, making a part of this specification. The nature of my invention
is as follows:

To enable others skilled in the art to make and use my in-
vention I will proceed to describe its construction. It is a single cast
iron plate - with an ornamental top, which as a cheap and lasting
Tomb or monument can be made for general use - It can be painted
with any colour, and gilded if wished. Its construction is such, that
when placed on the ground, it remains firmly fixed in its position. The
head or top of the plate or Tomb is to be cast with the design and
ornament herein described. It is intended principally for those Districts
of our Country, where marble cannot be easily obtained and in every
and every District can be furnished at such cheap prices as to enable
all persons of all classes and communities who would desire to have
a Tomb or Monument, to mark the place where their friends are
buried, whilst its durability cannot be questioned.

Figure 1 represents a view of "Cemetery Tomb" made of cast iron ha-
ving raised edges at each side and projecting ends underneath, and
a ledge curving from one of the lower ends to the other lower end
for the purpose of retaining its upright position permanently in
the ground when placed at the head of the grave. The head of
the plate or tomb is ornamented with the emblem of affection
- two doves resting in their nest, encircled by a raised ornate

Montal scroll work

What I claim as my invention and desire to
have letters patent is the ornamental design for a chest case "Coffre
Aux Tombes" ornamented as herein described:
